(57) **CLAIM**

The ornamental design for a camera cable routing plate, as shown and described.

DESCRIPTION

FIG. 1 is a front top perspective view of a camera cable routing plate shown in accordance with our new design; FIG. 2 is a front bottom perspective view of the camera cable routing plate shown in FIG. 1;

FIG. 3 is a rear top perspective view of a camera cable routing plate shown in FIG. 1;

FIG. 4 is a rear bottom perspective view of the camera cable routing plate shown in FIG. 1;

FIG. 5 is a front elevation view of the camera cable routing plate shown in FIG. 1;

FIG. 6 is a rear elevation view of the camera cable routing plate shown in FIG. 1;

FIG. 7 is a left side elevation view of the camera cable routing plate shown in FIG. 1;

FIG. 8 is a right side elevation view of the camera cable routing plate shown in FIG. 1;

FIG. 9 is a top plan view of the camera cable routing plate shown in FIG. 1; and,

FIG. 10 is a bottom plan view of the camera cable routing plate shown in FIG. 1.

The features shown in broken lines are for the purposes of showing environmental structure and form no part of the claimed design.
